UNITED STATES PATENT OFFICE.

FRANK A. HILL AND WILLIAM E. SHEHAN, OF ST. LOUIS, MISSOURI.

ATTACHMENT FOR LINOTYPE-MACHINES.

SPECIFICATION forming part of Letters Patent No. 602,904, dated April 26, 1898.

Application filed May 6, 1897. Serial No. 635,311. (No model.)

To all whom it may concern:

Be it known that we, FRANK A. HILL and WILLIAM E. SHEHAN, citizens of the United States, residing in the city of St. Louis, State 5 of Missouri, have invented a certain new and useful Improvement in Attachments for Linotype-Machines, of which the following is a full, clear, and exact description, reference being had to the accompanying drawings, forming 10 a part of this specification, in which—

Figure 1 is a view of a portion of the vise and knife-block of a linotype-machine, showing our improved attachment attached to the knife-block. Fig. 2 is a horizontal sectional 15 view through the knife-block and its associate parts, showing our improved attachment in an operative position; and Figs. 3, 4, and 5 are detailed views of slugs with which the movable knife coöperates.

20 This invention relates to a new and useful improvement in attachments for linotype-machines, and particularly to that part of the linotype-machine which gages the ribs on the issuing slugs after they have been molded. 25 For the purpose of separating the slugs certain distances apart, which is commonly known as "leading," we have devised this attachment, by which we are enabled to instantly change the mold-knives (without the assistance of a machinist) by raising or lowering a small lever placed within easy reach of the operator, whereby the operator can at will set solid or thin (one point) or thick (two points) leaded type.

30 The object of this invention is to provide mechanism for readily and quickly adjusting the movable knife so that said knife will shave the ribs on the slugs as desired.

Another object in view is to provide means 40 for smoothing down the burs or fins formed on the ribbed side of the slug, which are present when the ribs are left on the slug or are but partially removed.

With these objects in view the invention 45 consists in the construction, arrangement, and combination of the several parts for accomplishing the above, all as will hereinafter be described and afterward more fully pointed out in the claims.

50 In the drawings, A indicates the mold-disk,

B the vise, C the galley, and D the knife-block, all such parts being of ordinary construction.

E indicates the stationary knife, mounted on the vise.

F indicates the movable knife, preferably 55 mounted in a recess in the face of the knife-block.

G indicates screws formed with right and left hand threads engaging, respectively, the 60 movable knife and the knife-block.

H indicates arms mounted on the outer ends of screws G.

I indicates a link connecting the outer ends of arms H.

J indicates a sector or segment arranged on 65 the side face of the knife-block D.

K indicates a handle pivoted to the inner end of sector J, said handle being provided with a retaining-pawl for engaging the notches in the periphery of sector J. 70

L indicates a pin fixed in handle K and engaging link I.

From the above description it will be obvious that when handle K is raised or lowered it will partially rotate, through its connected mechanism, the screws G, and said screws will impart a lateral movement to the movable knife F, forcing said knife toward or from the stationary knife E. As seen in Fig. 2, knife F is adjusted relative to knife E, so 80 that the slug after being passed between the cutting edges of said knives will be solid matter. The ribs on the side of the slug are therefore shown as being shaved off almost entirely. By adjusting the handle K into 85 another notch on sector J, so that knife F is moved farther away from knife E, a lesser portion of the ribs on the slugs will be shaved off, as shown in Fig. 4. By adjusting the handle K to another notch on sector J the 90 knife F will be moved so far from knife E that the slug will practically pass between the two blades intact, knife F removing only a sufficient portion of the ribs to make the slugs of uniform thickness throughout their length. 95

It has been found from experience that when the slug is issued from the machine with full-sized ribs a fin or bur will be left near the type edge of the slug and between the ribs, as shown in Fig. 3, and while this fin is 100

- not a serious objection to the slug it deteriorates from its appearance when in the gallery. We have therefore grooved the plate L', which fits in the inside face of the knife-block, 5 to permit these ribs to pass in said groove, (shown at l,) so that the outer edge of said plate, which is held close to the vise by a spring l', will rub against the plain surface of the slug and smooth down this fin or bur. 10 We are aware that many minor changes in the construction, arrangement, and combination of the several parts of our device can be made and substituted for those herein shown and described without in the least departing from the nature and principle of our 15 invention.

Having thus described our invention, what we claim, and desire to secure by Letters Patent, is—

- 20 1. In a linotype-machine, the combination with the knife-block, of the stationary and movable knives, and a plate yieldingly supported in the inner face of the knife-block for engaging the slug as it issues from the machine and smoothing down any fins or burs which may be present on the type edge of the slug, said plate being provided with a plurality of grooves arranged in line with the ribs on the slug, whereby said ribs fit into the 25 grooves and permit the body portion of the 30

slug to fit close against the plate, as the slug is forced past the plate; substantially as described.

2. The combination with a knife-block, of a movable knife mounted therein, of a right 35 and left hand screw which engages the movable knife and the knife-block at its differently-threaded portions respectively, arms on the ends of said screws, a link connecting said arms, a lever engaging said link for moving the same and the screws simultaneously, and a sector with which said lever co-operates; substantially as described.

3. The combination with a knife-block, of a stationary knife and a movable knife, 45 screws G engaging the ends of the movable knife, arms H on the ends of screws G, a link I connecting the outer ends of arms H, a handle K connected to link I, a notched sector J, and a retaining-pawl on handle K which 50 co-operates with the notches on the periphery of sector J; substantially as described.

In testimony whereof we hereunto affix our signatures, in presence of two witnesses, this 27th day of April, 1897.

FRANK A. HILL.

WILLIAM E. SHEHAN.
